UNITED STATES PATENT OFFICE

HERBERT S. POLIN, OF SAN FRANCISCO, CALIFORNIA, ASSIGNOR TO POLIN, INC., OF NEW YORK, N. Y., A CORPORATION OF DELAWARE

DESIGN FOR AN AUDIPHONE

Application filed August 20, 1930. Serial No. 36,711. Term of patent 14 years.

To all whom it may concern:

Be it known that I, HERBERT S. POLIN, a citizen of the United States, residing at San Francisco, in the county of San Francisco, and State of California, have invented a new, original, and ornamental Design for an Audiphone, of which the following is a specification, reference being made to the accompanying drawing, forming a part thereof.

Fig. 1 is a perspective view of the audiphone showing my new design;

Fig. 2 is a side view.

I claim:—

The ornamental design for an audiphone as shown.

HERBERT S. POLIN.
